UNITED STATES PATENT OFFICE.

HENRY L. LEILICH AND JOHN P. BURGER, OF DELPHOS, OHIO, ASSIGNEES TO THE DELPHOS MANUFACTURING COMPANY, OF DELPHOS, OHIO, A CORPORATION OF OHIO.

SHEET-TRIMMING AND EDGE-FOLDING MACHINE.

971,905.

Specification of Letters Patent.

Patented Oct. 4, 1910.

Application filed December 13, 1909. Serial No. 532,759.

To all whom it may concern:

Be it known that we, HENRY L. LEILICH and JOHN P. BURGER, citizens of the United States, and residents of Delphos, in the county of Allen and State of Ohio, have invented a new and useful Sheet-Trimming and Edge-Folding Machine; and we do hereby declare the following to be a full, clear, and exact description of the invention, such as will enable others skilled in the art to which it appertains to make and use the same, reference being had to the accompanying drawings, and to the figures and letters of reference marked thereon, which 15 form a part of this specification.

Our invention relates to sheet metal working machines, and particularly to machines for trimming and folding the edges of sheet metal or the like to adapt the interlocking 20 of the edge of one sheet to the correspondingly folded edge of another sheet.

The object of our invention is the provision of a machine of this class which is simple, efficient and rapid in its operation, 25 and automatically operative to act on a strip of sheet metal or the like to trim and form successive folds in an edge thereof, whereby to minimize the expense incident to the trimming and folding of metal strips and 30 enhance the practicability and commercial value of machines of this nature.

A further object of our invention is the provision in a machine of this class of means 35 for automatically stamping each sheet operated on with any desired matter or information, thus obviating the necessity of a separate operation for such purpose.

The invention is fully described in the following specification, and while in its 40 broader aspect such invention is capable of embodiment in numerous forms, a preferred embodiment of the same is illustrated in the accompanying drawings, in which,—

Figure 1 is a side elevation of the machine 45 in its normal at rest position, with different internal parts shown in dotted lines. Figs. 2 and 3 are rear and front elevations, respectively, of the same. Fig. 4 is a top plan view of the same. Fig. 5 is a view of the 50 cams showing their relative arrangement. Fig. 6 is a corner portion of a sheet of work after being trimmed. Figs. 7 and 8 are successive stages of the folding operation of the edge of a sheet, and Fig. 9 is a cross section

of portions of the work trimming, folding 55 and clamping parts.

Referring to the drawings, 1, 1 designate the two side standards of the machine frame, which are braced by a frame part 2, and rigidly connected near their upper ends by 60 a horizontal table plate or part 3 and forwardly of such table plate by a knife-carrying table part 4. This latter table part has its upper surface in a common plane with the table 3, and is shown in the present instance as resting for horizontal adjustment on ledges or shelves 5 formed on the inner sides of the standards, being held in adjusted position thereon by screws 6, which work through slots in the ledges and thread into 65 the table part. A knife 7 is adjustably fixed to the forward edge of the table part 4 by screws 8 and 9, the latter of which thread upwardly through a ledge 10 on the forward side of said table part and bear against the 70 lower edge of the knife, see Fig. 3.

The standards 1 at the ends of the table parts 3, 4 are continued above such parts and each is provided with vertical guide-ways 11 and 12, in the former of which the 75 ends of a cross-head 13 are mounted for vertical reciprocating movements. A knife 14 is carried by this cross-head for coöperating with the lower fixed knife 7, on a downstroke of the cross-head, to trim the 80 interposed edge of a strip of work. Gage-stops 15 for the work are carried by the cross-head 13 and project down in advance 85 of the table-part 4, as shown in Fig. 3. The knife 14 is preferably set on an incline to 90 have a more efficient action. 16 designates a second cross-head which is disposed above the table 3 and has its end mounted for vertical movements in the guide-ways 12. This cross-head has its base transversely 95 broadened to form a pressure foot adapted to coöperate with the table 3 to clamp work thereto, and has a toe 17 which tapers forwardly to a point, which when the foot is lowered substantially registers with the forward edge of the table 3, as shown in Fig. 9. The cross-head or clamping member 16 is normally held elevated by compression springs 18 and has its lowering or clamping movements actuated by mechanism herein- 100 after described.

Disposed at the rear of the table 3 is a horizontal reciprocating work holding table

19, which has its surface in a plane with the table 3 and its ends mounted for sliding movements in guide-ways 20, mounted on the rear top portions of the standards 1. 5 A U-frame 21 has its loop portion or cross-bar disposed above the forward end of the table 19 and its arms extending rearwardly and pivoted as at 22, to ears rising from the table ends adjacent the rear edge thereof, 10 see Figs. 1, 2 and 4. The forward end of the frame 21 is normally held elevated above the table by the action of compression-springs 23 disposed therebetween. Yieldingly carried at the underside of the forward end of the frame 21 is a pressure-foot 24, which has guide-pins 25 projecting upwardly therefrom through registering apertures in the cross-bar of the frame, the lowering movements of which pins relative to 15 the cross-bar are limited by cotter-pins 26, see Figs. 1 and 4. The foot 24 is held yieldingly spaced from said cross-bar by compression-springs 27, Fig. 1. A boss 28 rises from each arm of the frame 21 and has its 20 top formed with a cam surface 29, with which a roller 30 carried at the end of a superposed arm 31 coacts. The arms 31 are carried by a rock-shaft 32, which is disposed above the frame 21 and has its ends journaled in bearing standards 33 rising from the ends of the table 19. On a rocking of 25 this shaft, as hereinafter described, in a direction to throw the arms 31 forward, the coaction of the rollers 30 with the cam-surfaces 29 causes a lowering of the forward end of the frame 21 to cause the pressure-foot 24 to yieldingly coöperate with the table 19 to grip an interposed strip of work. 30 designates an oscillatory folding member, which is disposed in the space between the tables 3 and 4 and has its ends provided with trunnions 35 journaled in the standards 1. The member 34 in the present instance is shown as comprising in cross-section, a quadrant or quarter of a shaft, the flat or radial lines of which radiate from the axis of the trunnions 35. The member 34 is so mounted that one of its flat or radial lines is normally disposed in the plane of 35 the tables 3, 4 and serves as the folding surface of such member, while its other radial line extends downwardly, as shown in Fig. 9. This shaft or folding member has its 40 folding movements actuated by mechanism 50 hereinafter described.

Mounted transversely of the machine with its ends journaled in the lower portions of the frame standards 1 is a main drive-shaft 36, on one end of which without the frame 60 is a belt-pulley 37. A shaft 38 is mounted in the frame standards above the shaft 36 parallel therewith and carries a loose pinion 39, which meshes with and is driven by a smaller pinion 40 on the shaft 36. Fixed 65 to the shaft 38 at one side of the pinion

39 is a fixed collar 41 carrying a pin clutch-member 42, which is normally held out of engagement with a complementary clutch surface in the pinion hub by a release member 42', which works in a peripheral groove in 70 the collar and, when lowered, coacts with the headed end of the pin 42 to effect its release from the pinion hub at the end of a completed revolution of the shaft in a manner well known in the art. The shaft 38 75 also has a set of cams 43 and 44 on each end thereof without the standard 1, a cam 45 adjacent the inner side of each standard, and a cam 46 intermediate said latter cams.

The cams 43 are intended to actuate the 80 movements of the cross-head or work clamping member 16 and for this purpose each acts on a roller 47 carried at the lower end of an associated rod or pitman 48, which attaches at its upper end to a stud 49 projecting from an end of the cross-head and has its lower end pivoted to the free end of an arm 50, which pivotally projects from a stud 51 on the standard 1.

The cams 43 are adapted in the present 90 instance to effect a lowering of the member 16 to clamp the work at substantially the end of a half revolution of the shaft 38 and to maintain such member depressed until the remainder of the revolution of the 95 shaft is nearly completed, except for a slight raising movement during the period of depression due to the rollers 47 working into recesses or depressions *a* in the neutral or concentric surface *b* of the cams, for the 100 purpose hereinafter described.

The cams 44 are for the purpose of actuating the rocking movements of the rock-shaft 32 to effect clamping and releasing movements of the pressure-foot 24. To this 105 end said cams are made pointed as shown and each acts on a roller 52 carried at an end of a lever 53, which is fulcrumed to a frame stud 54 and has its other end connected by a link or bar 55 to a crank-arm 110 56 projecting from the rock-shaft 32. It is thus apparent that on a raising of the roller ends of the lever 53 by the coaction of the cams 44 therewith, which is timed to take place at the beginning of a revolution of 115 the shaft 38, the rock-shaft 32 will be rocked to throw the rollers 30, carried by the arms 31, into position to effect a clamping action of the U-frame 21 and pressure-foot 24 to hold the work to the table 19. 120

Toggle-links 57, 57 connect the frame studs 51 with the rear end portions of the levers 53 at each side of the machine, and one of each set carries a roller 58 at its inner end, which, on a clamping movement of the 125 associated lever 53, is thrown forward into the path of movement of the pointed end of the cam 44 in position to be engaged by such cam when near the completion of its revolution. This engagement of the cams 130

44 with the rollers 58 of the toggle sets effects a straightening movement of the toggles and a consequent positive releasing movement of the clamping parts, as is apparent.

The cams 45 are intended to control the rearward reciprocatory movements of the work-holding table 19 through the medium of the vertical rock-arms 59, carried loosely at opposite end portions of a shaft 60, connecting the frame standards, and the links or bars 61, which connect the upper ends of said arms with lugs 62 projecting from the under side of the table 19, as shown in Figs. 1 and 2. A roller 63 is carried at the forward side of each arm 59 and coacts with the associated cam. Each cam 45 is formed with the cam surfaces *c*, *d* and the two intermediate neutral surfaces *e*, *f*, which are in concentric planes, with the former more remote from the cam axis, whereby movements are imparted to the table 19 as hereinafter fully described. The forward movements of the table 19 are caused by contraction springs 65, which attach at their rear ends to the table 19, as at 66, and at their forward ends to collars 67 on the shaft 67', which has its ends mounted in the standards 1.

30 The cam 46 is for the purpose of acting on a roller (not shown) on a side of the vertically disposed arm 68, mounted loosely on the shaft 60, whereby to rock said arm at predetermined intervals to impart rocking movements to a rock-shaft 69 through the medium of a link or bar 70, attached to the free end of said arm, and a rock-arm 71 on the shaft 69, as shown in Figs. 1, 2 and 3. The shaft 69 is journaled in the frame standards and above the plane of the shaft 38, and carries an arm 72 at each end without said standards. The arms 72 extend upwardly from the shaft and each terminates at its upper end in a toothed segment 73 which meshes with a pinion 74 carried at the outer end of the adjacent trunnion 35 of the folding member 34. The cam 46 is formed on one side thereof with the two radial projections *g* and *h*, which, on a revolution of such cam, act on the rock-arm 68 to impart successive rocking movements to the folding member 34 to first form the initial fold *i* at the edge of a strip of work A and then to form the second or successive fold *j* therein, as shown in Figs. 7 and 8. As the first fold *i* is pressed more closely to the plane of the work-strip than the subsequent fold *j* as shown, the projection *g* is slightly longer than the projection *h* of the cam to adapt one to effect a greater throw of the arm 68, and consequent greater degree of rocking of the folding member 34, than the other. The arm 68 has its forward movements caused by a contraction-spring 75, which attaches at its rear end to such arm and at its forward

end to the table 3, thus tending to normally maintain the folding member 34 with its folding surface in a plane with the top surfaces of the tables, 3, 4 and 19.

Projecting downwardly from the ends of the cross-head 13 at the sides of the machine frame are rods 76, which carry straps 77 at their lower ends for encircling eccentricities 78 on the ends of a subjacent shaft 79. This shaft is journaled in the frame standards and carries a loose pinion 80 in mesh with the pinion 39 on the shaft 38, and also carries a single-revolution type of clutch mechanism 81 of similar construction to the clutch 41-42 on the shaft 38, whereby on a release of the clutch member thereof the pinion 80 is engaged to communicate a single revolution to the shaft 79 and a consequent down and up-stroke of the cross-head 13. The release member 42', which controls the actions of the clutch-pin 42, is of T-form with one arm coacting with the clutch 41-42, as previously described, and its other arm coacting in a similar manner with the pin 82 of the clutch mechanism 81, whereby a raising of such release member effects a simultaneous release of both clutches to engage their respective pinions.

The member 42' is attached to the upper end of a rod 83, which is guided for vertical movements by a standard 84, see Figs. 2 and 3, and is normally held in lowered position by a compression-spring 85, which encircles said rod and has its ends thrust against a shoulder 86 on such rod and a part of the guide standard 84. The lower end of the rod 83 bears on an arm 87 projecting horizontally from a rock-shaft 88, which is journaled in the lower portion of one of the standards 1 and a bearing-block 89, and has a foot-treadle 90 projecting therefrom in opposition to the arm 87.

91 designates a brake-strap which connects and encircles brake-disks (not shown) mounted on the shafts 38 and 79, thus tending to stop the rotation of such shafts on a release of the clutch mechanisms 41-42 and 81 from the respective pinions 37 and 80.

Mounted beneath the table 3 in one frame standard 1 and a pedestal bearing 92 is a shaft 93, which carries a pinion 94 in mesh with a smaller pinion 95 on the shaft 38, see Figs. 2 and 3. The shaft 93 also carries a cam 96 on which a roller 97 carried at the lower end of a die-block 98 rides. The die-block 98 works through an opening in the table 3 beneath the clamping member 16, and is raised at each revolution of the cam 96 to cause it to act in opposition to such clamping member to impress or stamp any desired information on the work.

In the use of our machine, the operator feeds a sheet of metal or other work to be operated on forward between the table 19 and pressure-foot 24 and the table 3 and

clamping member 16 until stopped by contact with the gages 15 carried by the cross-head 13. The operator then depresses the treadle 90 to raise the clutch controlling member 42' to effect a simultaneous release of the clutch-pins of both clutches 41—42 and 81—82 to permit such pins to move into engagement with the respective pinions 39 and 80 whereby to rotate the shafts 38 and 79 with such pinions. As the pinions 39 and 80 are in proportion of two to one and the pinion 39 serves as the drive, it is apparent that the pinion 80 will have a complete revolution imparted thereto, whereby 10 to lower and raise the cross-head 13 to trim the forward edge of the work, while the pinion 39 is making a half turn. Immediately upon the commencement of a single rotation of the shaft 38, or substantially so, 15 and prior to the trimming operation, the cams 44 at the ends thereof act on the rollers 52 carried at the ends of the levers 53 to effect movements of such levers in the proper direction to lower the bars or links 55 and 20 rock the shaft 32 to impart a lowering or clamping movement to the forward end of the U-frame 21 and pressure-foot 24 carried thereby, whereby to coöperate with the table 19 to firmly grip the work. Upon a 25 trimming of the edge of the work which takes place at approximately the completion of a quarter revolution of the shaft 38, the cam surfaces *e* of the two cams 45 move into contact with the rollers 63 of the arms and 30 effect a movement of the work-holding table 19 to the limit of its rearward movement through the medium of the links or bars 61, which position the table maintains for a 35 predetermined length of time by reason of said rollers operating on the neutral surfaces of the cams 45. The rearward movement of the table 19, which is thus effected, is sufficient to withdraw the work A from the trimming parts until its trimmed edge projects 40 a desired distance beyond the nose 17 of the clamping member 16 for the formation of the fold *i* therein. At this point in the cycle of operations the cams 43 act on the rollers 45 to lower the rods 48 and attached clamp- 45 ing member 16 to clamp the work to the table 3 immediately to the rear of the folding member 34. As soon as the work has been clamped by the member 16 the folding-member 34 is oscillated to fold the projecting 50 edge of the work over the toe 17 of said clamping-member due to the arm *g* of the cam 46 acting on the arm 68 to impart a forward rocking movement to the segment arms 72 through the medium of the rock-shaft 69, link 70 and rock-arm 71. As the roller on the rock-arm 68 passes over the arm *g* of the cam 46 it drops into a depression *g'* of such cam to permit the return of the folding-member 34 to its normal position under 55 the influence of the springs 75. Simulta-

neous with such action the clamping member 16 is instantaneously released from the work and again lowered into clamping engagement therewith due to the rollers 47 at the ends of the rods 48 working into the recesses *a* in the neutral surfaces *b* of the cams 43. During this instantaneous release of the clamping member 16 from the work, the rollers 63, carried by the arms 59 of the mechanism controlling the movements of the table 19, drop to the neutral surfaces *f* of the cams 45 thus permitting the forward movement of the table 19 under the influence of the springs 65 and effecting a forward movement of the work relative to the folding parts. This movement is so regulated that a sufficient length of the work is projected beyond the toe of the clamping member 16 to provide for the subsequent or second fold *j* therein. The folding member 34 is now oscillated to form the fold *j* in the work due to the second arm *h* of the cam 46 coacting with the roller carried by the arm 68 of the mechanism for operating the folding member. The degree of movement, however, of the member 34 in the forming of this latter fold is not so great as the movement thereof during the forming of the first fold, due to the arm *h* being shorter than the arm *g*, thereby imparting a fold to the work as shown in Fig. 8. Upon the completion of this fold, the cams 43 have moved to a point to permit a release of the clamping member 16, the cams 45 then release the mechanism actuating the rearward movements of the table 19 to permit such table, under the influence of the springs 65, to move to the end of its forward stroke, and the cam 44 then strikes the rollers 58 carried by the toggle links 57 to effect a partial straightening of such links and a consequent positive releasing movement of the rollers 30 on the cam surface 29 of the U clamping frame 21 whereby an upward or releasing movement of such frame under the influence of the springs 23 is permitted. This completes the cycle of operations of the machine, the parts being in the position in which they were before the treadle 90 was depressed and permitting a withdrawal of the folded work 115 therefrom and the insertion of either the opposite end of such work sheet or the end of another sheet to be acted on.

At a predetermined point in the cycle of operations or when the member 16 is lowered in clamping position, the cam 96 carried by the shaft 93 acts on the roller 97 at the lower end of the die block 98 to effect a raising of such die to stamp the name of the company putting out the work, or any other desired information, on the work sheet, such die acting in opposition to the clamping member 16 in such stamping operation. In the present instance, the cam 96 is adapted to act on the die at each second cycle of opera- 125 130

tions of the machine due to the driving pinion 95 being one-half the size of the driven pinion 94 on the shaft 93. This is done to prevent the work from being stamped twice 5 when opposite ends of the same are operated on at the next operation.

It is apparent that we have provided a machine which is entirely automatic in its 10 operation and which is adapted, during a single cycle of operations, to trim the edge of a sheet placed therein, move the sheet back to folding position, clamp the same in such position, form the initial fold therein, then release the sheet and move it forward 15 in position for the next fold, after which the final fold is made and the parts then returned to their normal positions, leaving the folded work in condition to be removed from the machine and replaced by another 20 piece of work to be operated on. These different operations being entirely automatic and following one another in rapid succession provides a machine, which, with the attendance of a single operator performs the 25 work for which it has heretofore been necessary to employ several workmen and very materially increases the output due to the rapid operation of the same.

We wish it understood that our invention 30 is not limited to any specific construction or arrangement of the parts of the same except in so far as such limitations are specified in the claims.

Having thus described our invention, what 35 we claim as new, and desire to secure by Letters Patent, is;

1. In a machine of the class described, the combination with edge folding means, of mechanism for automatically gripping the 40 work and moving it for successive folds.

2. In a machine of the class described, the combination with edge folding means, of mechanism automatically operative to grip the work, move it for successive folds and 45 then release it.

3. In a machine of the class described, the combination with edge folding means, of a reciprocating work gripping part at one 50 side of such means, and mechanism operative to cause said part to grip work fed thereto, move the same to receive successive folds and then to release the work.

4. In a machine of the class described, the combination with a frame, and edge folding means carried by the frame, of a reciprocating part mounted at one side of the folding means, means movable with such part for gripping work fed to the folding means, and mechanism operative to actuate said gripping means to grip and hold the work during the folding operations, and to move said part and gripping means to place the work in position to receive successive folds.

5. In a machine of the class described, the combination with work trimming means,

edge folding means spaced from said trimming means, and means associated with the folding means to clamp the work during the folding operations, of reciprocating means for gripping the work, and mechanism operative to actuate said reciprocating means to grip and hold the work during the successive trimming and folding operations, and to move the work from trimming to folding position.

6. In a machine of the class described, the combination of a frame having a table portion, edge trimming means and edge folding means arranged one in advance of the other along the table top, means adjacent the folding means movable to coöperate with the table to clamp the work thereto during the folding operations, movable work holding means, and mechanism operative to actuate the trimming means to trim the work, the folding means to fold the trimmed edge, the clamping means to coöperate with the table to clamp the work during the folding operation and the holding means to grip and hold the work and to move the work from cutting to folding position.

7. In a machine of the class described, the combination of a frame having a table part, work trimming means and work folding means arranged one in advance of the other 95 along such table, a clamping member for co-operating with the table to clamp the work during folding operations, reciprocally movable work holding means, and mechanism operative to actuate the trimming means to trim the work, the folding means to fold the work, the clamping means to coöperate with the table to clamp the work, and the holding means to grip the work and move the same from cutting to folding position and for successive folds.

8. In a machine of the class described, the combination of a frame having a table part, work trimming means and oscillatory edge folding means associated with such table 100 part and arranged one in advance of the other, a clamping member movable to co-operate with the table part to clamp the work during the folding operations, work gripping and controlling means, and mechanism operative in a single cycle of operations to actuate the trimming means to trim the work, to oscillate the folding means to form folds in the work, to move the clamping member to coöperate with the table part 110 to grip the work during the folding operation and to actuate the work gripping and controlling means to grip the work and move the same from trimming to folding position and for successive folds.

9. In a machine of the class described, the combination of a frame having a work supporting part, trimming means, and an oscillatory edge folding member associated with such part one in advance of the other, a 120

member arranged above and movable to clamp work to such part, a table reciprocally carried by the frame in the plane of such part to permit the feeding of work over such table, means for clamping the work to such table, and mechanism operative to sequentially actuate the table gripping means to grip the work, the trimming means and folding member to trim and fold an edge of the work, the clamping member to clamp work to the frame part during the folding operation, and the table and gripping means to move the work for successive operations and then move the gripping means to release the work.

10 10. In a machine of the class described, an oscillatory folding member, means for clamping the work and coöperating with the folding member to form folds therein, and mechanism for intermittently oscillating said member, intermittently moving the clamping means to grip and release the work, and to hold the work during and move the same for successive folds.

15 11. In a machine of the class described, a revolute folding member, and cam actuated mechanism for intermittently moving said member to make successive folds and to grip the work while being operated on and automatically move the same to receive such folds.

20 12. In a machine of the class described, edge folding means, work clamping means, and cam controlled mechanism for operating the folding means to make successive folds, the clamping means to intermittently grip and release the work and to hold the work from the beginning to the end of such operations and change the position of the same for the successive folds.

25 13. In a machine of the class described, a folding member, work clamping means associated therewith, movable work holding means, and cam controlled mechanism for operating the folding member to make successive folds, the clamping means to intermittently grip and release the work and the work holding means to grip and change the position of the work for successive folds.

30 14. In a machine of the class described, an oscillatory folding member, means for clamping the work and coöperating with the folding member to form folds therein, work holding means, and cam controlled mechanism for intermittently oscillating the folding member, intermittently moving the clamping means to grip and release the work, and acting on the work holding means to grip and change the position of the work for successive folds.

35 15. In a machine of the class described, a folding member, means adjacent such member for clamping the work, reciprocatory work holding means, and mechanism operative to actuate the folding member to

make successive folds, the clamping member to intermittently grip and release the work and the work holding means to change the position of the work for successive folds.

40 16. In a machine of the class described, an oscillatory folding member, work clamping means associated therewith, a reciprocatory table, means carried by the table for gripping the work, and mechanism operative to oscillate the said member to form successive folds, and to actuate the clamping means to intermittently grip and release the work, the table gripping means to hold the work stationary to the table, and the table to change the position of the work for successive folds.

45 17. In a machine of the class described, work cutting means, revolute folding means, and mechanism for actuating the work cutting means, imparting successive operations to the folding means, and moving the work from cutting to folding position and then changing its position for successive folds.

50 18. In a machine of the class described, work cutting means, oscillatory work folding means, work clamping means associated with the folding means, work holding means, and mechanism operative to actuate the cutting means to sever the work, the folding means to form successive folds therein, the clamping means to intermittently clamp and release the work, and the work holding means to grip and control the movements of the work for the successive cutting and folding operations.

55 19. In a machine of the class described, work cutting means, work folding means, work clamping means associated with the folding means, movable work holding means, and cam controlled mechanism for actuating the cutting means to cut the work, the folding means to form successive folds therein, the clamping means to intermittently grip and release the work, and the holding means to grip and control the movements of the work for the successive cutting and folding operations.

60 20. In a machine of the class described, work trimming means, an oscillatory folding member parallel with such means, a table part associated with said member, a clamping member movable to coöperate with said table part to hold the work during a folding operation, a reciprocatory work gripping part, and mechanism for operating the cutting means to sever the work, the folding member to form successive folds therein, the clamping means to intermittently grip and release the work, and the gripping means to first grip the work and then to move the work from cutting to successive folding positions.

65 21. In a machine of the class described, fixed and movable cutting parts, an oscillatory folding member, clamping means asso-

- ciated with such member, work gripping and controlling means, and mechanism operative in a single cycle of operations to move the movable cutting part to sever the work, to 5 oscillate the shaft to form successive folds in the work, to move the clamping means to intermittently grip and release the work, and the controlling means to first grip the work, then to move the work for successive 10 folding operations, and then to release the same.
22. In a machine of the class described, edge trimming means, edge folding means, clamping means associated with said folding 15 means, movable work holding means, a shaft, clutch controlled means for imparting intermittent single revolutions to such shaft, and mechanism operative by a rotation of 20 said shaft to actuate the trimming means to trim the work, the folding means to form successive folds therein, the clamping means to intermittently grip and release the work, and the holding means to grip and move the work from cutting to folding position and 25 for successive folds.
23. In a machine of the class described, cutting means, work folding means, a normally released clamping member associated 30 with the folding means, movable work holding means, and cam actuated mechanism adapted in a single cycle of operations to 35 actuate the cutting means to trim the work, the folding means to fold the trimmed edge of the work, the clamping member to clamp the work during the folding operation and 40 then to permit a releasing movement thereof, and the work holding means to grip and control the movements of the work for the successive operations and then to release the work.
24. In a machine of the class described, a folding member, means associated with 45 said member for clamping the work during the folding operations, movable work holding means, and mechanism operative to impart successive folding movements of different degree to said folding member, and to actuate the clamping means to intermittently grip and release the work, and the work holding means to grip and move the work for successive folding operations and then release the same.
25. In a machine of the class described, an oscillatory folding member, work gripping means associated with such member, 55 movable work holding means, and mechanism operative to impart successive folding movements of different degree to said folding member, to actuate the clamping means to intermittently clamp and release the work, and to actuate the work holding means to grip the work and move the same for successive folding operations and then to release the same.
26. In a machine of the class described, 60 fixed and movable coöperating cutting parts, a folding member disposed adjacent thereto, a clamping member associated with the folding member, slideable work holding means, a shaft, clutch controlled driving 65 means therefor, and mechanism operative by the shaft to actuate the movable cutter part to trim the work, the folding member to successively impart folds of different degree of inclination to the work, the clamping 70 means to intermittently grip and release the work, and the work holding means to grip and move the work into positions for successive operations and then to release the same.
27. In a machine of the class described, 75 the combination of work trimming means, work holding means, and mechanism operative to actuate the cutting means to sever the work and the holding means to grip and retract the work from the cutting means 80 after the cutting operation.
28. In a machine of the class described, the combination of work cutting means, 85 slideable work holding means, and mechanism operative to actuate the cutting movements of said cutting means and to cause said work holding means to grip the work and retract the same from cutting position after the cutting operation and then to release the work.
29. In a machine of the class described, 90 the combination of work trimming means, a slideable table, work gripping means associated with such table, and mechanism operative to actuate the cutting movements of 95 the cutting means, to move said gripping means to coöperate with the table to grip the work, to move the table and gripping means to retract the work from cutting position after the cutting operation, and to release the gripping means from the work.
30. In a machine of the class described, 100 the combination with work trimming means, work folding means, and work clamping 105 means associated with the folding means, reciprocating work-holding means, and mechanism operative to act on the work holding means to grip the work and to move such means to retract the work from cutting 110 position and after the first folding operation to move the work forward for the second folding operation.
31. In a machine of the class described, 115 the combination of work trimming means, work folding means, reciprocating work-holding means influenced to normally stand at one position of its movement, and mechanism operative to actuate the trimming means to trim the work, the folding means 120 to fold the trimmed edge of the work, and the work-holding means to grip the work and to recede it from its normal position to retract the work from trimming to folding 125 position.

32. In a machine of the class described, the combination of cutting means, edge folding means, clamping means associated with said folding means, reciprocatory work holding means influenced to normally stand in one position of its movement, and mechanism operative to actuate the cutting means to trim an edge of the work, the folding means to form successive folds in an edge of 65 the work, the clamping means to intermittently grip and release the work, and the work holding means to grip the work and to move it from its normal position to retract the work from trimming to folding position 70 and then to permit a predetermined movement of said holding means to move the work for the subsequent fold.
33. In a machine of the class described, the combination of work trimming means, 75 work folding means, work clamping means associated with the folding means, reciprocatory work-holding means influenced to normally stand in one position of its movement, a clutch controlled intermittently revoluble shaft, a series of cams carried by said shaft, and mechanism coöperating with said cams to impart trimming movements to said trimming means, folding movements to said folding means, clamping and releasing 80 movements to said clamping means, and to cause said holding means to grip the work, retract the same from trimming to folding position and then release the work during a single revolution of said shaft.
34. In a machine of the class described, a movable work controlling means adapted to grip the work, an intermittently revoluble shaft, and mechanism actuated by a revolution of the shaft to cause said controlling 85 means to grip the work and impart predetermined movements thereto.
35. In a machine of the class described, the combination of a reciprocatory work holding part, work clamping means associated with such part, an intermittently revoluble shaft, and mechanism actuated by a revolution of said shaft to operate the gripping means to coöperate with the work-holding means to hold the work and then 90 to move the work-holding and gripping means to impart predetermined movements to the work.
36. In a machine of the class described, the combination of reciprocatory work gripping means, an intermittently revoluble shaft, a cam carried by such shaft, and mechanism connecting said cam and means and operative by a movement of the cam to impart predetermined reciprocatory movements 95 to said means to move the work.
37. In a machine of the class described, the combination of a reciprocatory work holding table, work gripping means carried thereby, an intermittently revoluble shaft, 100 a cam carried by said shaft, mechanism actuated by said cam and connecting said cam and work gripping means to impart gripping movements to said means on a revolution of the shaft and then to effect a release of such gripping means, and mechanism 105 connecting said shaft and table for imparting predetermined reciprocatory movements to the table on a revolution of the shaft.
38. In a machine of the class described, the combination of a frame, a reciprocatory work controlling part, means associated with such part for gripping work thereto, a shaft, two cams on such shaft, means coöperating with one of such cams for causing gripping and releasing movements of said gripping 110 means during a revolution of such shaft, means coöperating with the other of such cams for imparting movements to said part in one direction, and means acting to impart movements to said part in the opposite direction.
39. In a machine of the class described, the combination of a frame, work holding means movable in said frame to control movements of work being acted on, means 115 acting on such means to influence such movements in one direction, a shaft, cams carried by such shaft, means actuated by one of such cams during a revolution of the shaft to effect a gripping of the work to 120 such means and a release of the same, and means actuated by another of such cams for imparting predetermined movements to said means in the opposite direction.
40. In a machine of the class described, 125 the combination of a frame, work folding means associated therewith, work gripping and controlling means movable in said frame, a plurality of revoluble cams, means actuated by one of said cams at predetermined points in a revolution thereof to effect gripping and releasing movements to said gripping means, and means actuated by another of said cams to impart predetermined work controlling movements to 130 said work gripping and controlling means to move the work to receive successive folds.
41. In a machine of the class described, the combination of a frame, work trimming means and work folding means associated 135 with such frame, a part movable relative to said trimming and folding means, means for moving said part in one direction of its movements, a plurality of cams, means coacting with one of said cams to impart predetermined work gripping and releasing movements to said part, and means coacting with another of said cams to impart work controlling movements to said part.
42. In a machine of the class described, 140 the combination of a frame, work folding means and work clamping means associated with such frame, a work gripping part mov-

able relative to said folding and clamping means, a plurality of revoluble cams, means for coöperating with one of said cams to impart predetermined folding movements to the folding means, means actuated by one of said cams to impart predetermined clamping and releasing movements to said clamping means, means actuated by one of said cams to cause said part to grip and release work at predetermined intervals, means coacting with one of said cams to impart predetermined movements in one direction to said part, and means acting on said part to move it in the opposite direction.

15 43. In a machine of the class described, the combination of a frame, work trimming means and work folding means associated with such frame, a part movable relative to said trimming and folding means, an oscillatory work clamping member carried by said part, and mechanism operative to impart predetermined movements to said part and member to move work for successive operations and to clamp and release 25 the work at predetermined intervals.

44. In a machine of the class described, the combination with work trimming means and work folding means, of a work-holding part movable to control the movements of the work while being acted on by said trimming and folding means, and mechanism for actuating said part to grip and release work fed thereto and to move such part to control the movements of the work for successive 35 operations.

45. In a machine of the class described, the combination of a frame having a work supporting part, an oscillatory edge folding member associated with such part, means for coöperating with said part to clamp the work thereto during the folding operations, means at one side of such part for gripping the work and moving the same for successive folding operations, and mechanism for imparting successive folding movements to said oscillatory member, moving the clamping member to intermittently clamp the work to the frame part and release the same for successive folding operations, and to actuate 50 the gripping means to grip the work during the folding operations and to move the work to receive successive folds.

46. In a machine of the class described, a frame having a work supporting part, edge folding means associated with such part, a clamping member movable to coöperate with said part to clamp work during the folding operation, means for gripping the work and controlling the movements of the same while 60 being acted on, and mechanism operative to impart successive folding movements to said folding means, to intermittently move the clamping member to clamp the work to the table for each folding operation and then

to release the same and to actuate the work gripping means to grip the work while being acted on and move the same to receive successive folds.

47. In a machine of the class described, the combination of a frame having a work supporting part, an oscillatory folding member associated with such part, means for coöperating with said part to clamp the work during a folding operation, a table reciprocally movable at one side of said part, a part carried by such table for coöperating therewith to grip the work, and mechanism operative to intermittently oscillate said folding member, intermittently move the clamping means to clamp and release the work for successive folds and to actuate said table part to coöperate with the table to grip the work and move said table and gripping part to control the movements of the work to receive successive folds. 85

48. In a machine of the class described, the combination of a frame having a work supporting part, an oscillatory folding member associated with such part, yieldingly movable clamping means movable to intermittently clamp the work to said part and release the same for successive folds, a reciprocating table movable in the plane of such part, means carried by such table for clamping work, and cam controlled mechanism operative in a single cycle of operations to intermittently oscillate the folding member for successive folds, to actuate the clamping means to intermittently grip and release the work during the folding operations and to 100 actuate said gripping means to grip the work to said table and to actuate the table to move the work to receive successive folds.

49. In a machine of the class described, a frame having a work supporting part, edge trimming means and edge folding means associated with such part and arranged one in advance of the other, a member yieldingly movable to clamp work to such part, work gripping means disposed adjacent the edge 105 of said part which is opposed to the trimming means and movable toward and away from said part, means acting on said gripping means to yieldingly hold it in one position of its movement, and mechanism operative to actuate said gripping means to grip work and to coöperate with said yielding means to move the work to receive the folds. 110 115

50. In a machine of the class described, a frame having a work supporting part, means operative to trim an edge of sheet-metal work; the work trimming and folding parts of said two means being associated with said table part and arranged one in advance of the other, means operative to successively clamp work to said part during the folding operation and release the same, a table re- 120 125

ciprocally movable at a side of the frame part, a clamping member for coöperating with such table to grip work thereto, means yieldingly acting on the table to normally retain it in one position of its movement, and mechanism operative to actuate said clamping member to clamp the work and to co-operate with said yielding means to move the table to move the work from cutting to folding position and for successive folds.

51. In a machine of the class described, the combination of a frame having a work supporting part, work trimming members and an oscillatory work folding member associated with such part, an element movable to clamp work to such part during folding operations, a work holding and controlling part movable in such frame, oscillatory means associated with such holding part for 15 clamping work thereto, a revolute shaft, means for communicating trimming movements to said trimming members at a predetermined point in a revolution of the shaft,

means actuated by said shaft for imparting folding movements to said folding member 25 at predetermined points in a revolution of the shaft, means actuated by such shaft for actuating said clamping element to intermittently clamp and release the work, means actuated by said shaft to impart predetermined work controlling movements to said work holding part during a revolution of the shaft, means actuated by said shaft to impart work gripping and releasing movements to said oscillatory means at predetermined points in a revolution of the shaft, and means influencing a movement of said work holding part in one direction.

52. In testimony whereof, we have hereunto signed our names to this specification in the presence of two subscribing witnesses.

HENRY L. LEILICH.
JOHN P. BURGER.
